(57) **CLAIM**

The ornamental design for a computer as shown and described.

DESCRIPTION

FIG. 1 is a right, front, and top perspective view of a computer, showing my design;

FIG. 2 is a right, front, and top perspective view of the computer in FIG. 1 in a closed state;

FIG. 3 is a left, rear, and top perspective view of the computer in FIG. 1 in the closed state;

FIG. 4 is a front elevational view of the computer in FIG. 1 in an opened state;

FIG. 5 is a rear elevational view of the computer in FIG. 1;

FIG. 6 is a top plan view of the computer in FIG. 1;

FIG. 7 is a bottom plan view of the computer in FIG. 1;

FIG. 8 is a right-side elevational view of the computer in FIG. 1;

FIG. 9 is a left-side elevational view of the computer in FIG. 1;

FIG. 10 is an enlarged view of an area “10” identified in FIG. 1;

FIG. 11 is an enlarged view of an area “11” identified in FIG. 1;

FIG. 12 is an enlarged view of an area “12” identified in FIG. 8;

FIG. 13 is an enlarged view of an area “13” identified in FIG. 8; and,

FIG. 14 is an enlarged view of an area “14” identified in FIG. 8.

The evenly-dashed broken lines shown in the drawings are included for the purpose of illustrating portions of the computer that form no part of the claimed design. The

(Continued)

dot-dashed broken lines in FIGS. 1, 8, and 10-14 framing portions of the computer for enlargement purposes form no part of the claimed design.

1 Claim, 7 Drawing Sheets
